[57] CLAIM

The ornamental design for a golf driving range mat for authentic practice, as shown and described.

DESCRIPTION

FIG. 1 is a top, right perspective view of the golf driving range mat for authentic practice, the broken line showing of wording is for illustrative purposes only and forms no part of the claimed design;

FIG. 2 is a top view thereof;

FIG. 3 is a right side view thereof, the left side being in essence a mirror image thereof;

FIG. 4 is a front view thereof; and

FIG. 5 is a rear view thereof.

FIG. 6 is a top, perspective view of a mat as of FIG. 1 less the attachable indicia-bearable member, showing my new design; and,

FIG. 7 is a top, perspective view of a mat as of FIG. 1 less the attachable set of ball-holding trays, showing my new design.
